UNITED STATES PATENT OFFICE

HARRY GLAENZER, OF PHILADELPHIA, PENNSYLVANIA

AIR PUMP AND POWER REVERSE SUPPORT

Application filed July 28, 1930. Serial No. 471,386.

The object of this invention is to dispense with the brackets which are usually secured to the boiler of a locomotive and which support the air pump and power reverse, and to 5 substitute therefor supports for said air pump and power reverse cylinders which are mounted directly on the main frame of the locomotive and independent of the boiler. This 10 object I attain in the following manner, reference being had to the accompanying drawings, in which:

Fig. 1 is a view in elevation illustrating my improved supports for air pump and power reverse mechanism, and showing the side 15 frames of the locomotive in section, the structure being in the form of an internal casting;

Fig. 2 is a plan view;

Fig. 3 is a side view;

20 Fig. 4 is a modification showing a support for the air pump;

Fig. 5 is a view of a modification showing a support for the power reverse; and

25 Fig. 6 is a view similar to Fig. 1, showing the welded structure made in accordance with my invention.

1—1 are the side frames of the locomotive. The boiler 2 is shown by dotted lines in Fig. 1. 3 is an integral casting having feet 4 30 which rest upon the side frames 1, and having heels 5 which extend on the inner side of each frame, as shown in Fig. 1. The structure is rigidly secured to the side frames of the locomotive in any suitable manner. 6

35 8 is one type of an air pump which is mounted on the locomotive and 7 indicates one type of power reverse. These parts may be modified, however, without departing from the essential features of the invention.

40 8 is a bracket forming an integral part of the main structure 3 and has pads 9 to which is secured the air pump 6. The bracket consists of two side frames 10—10a. One of these side members 10a extends to the foot 4 at the

45 opposite side of the locomotive from the air pump, while the other side member 10 extends to a bracket 11, to which is secured the cylinder of a power reverse device. Other parts of the device may be secured to the bracket 50 and the cylinder may over hang, depending

upon the type of power reverse used. Forming part of the bracket 11 is a strut 12, which extends to a point about midway between the two frames and is made integral with the cross bar 13.

The feet 4 of the structure are extended as shown, so as to give a firm bearing on the frame, and the feet at each side of the structure are connected by the cross bar 13 and bars 14.

The structure may be lightened considerably as shown in the drawings without materially decreasing the strength of the structure.

As shown in Fig. 1, this structure is securely 65 fastened to the main frame of the locomotive and is independent of the boiler, and as the air pump and the power reversing cylinder are directly opposite in certain types of locomotives, the structure may support both the 70 air pump and the power reverse cylinder, but where the two parts are not opposite, then the bracket for the air pump may be made as shown in Fig. 4 and the bracket for the power reverse may be made as shown in Fig. 75 5, but in either case these brackets are carried by the main frame and are not connected to the boiler.

While two side frames are shown in Fig. 1, which are connected together and which support the structure, the structure may be secured to cast steel integral locomotive frames without departing from the essential features of the invention.

In Fig. 1 the structure is shown as being 85 made as an integral casting but the structure may be made of wrought metal shapes, as shown in Fig. 6, without departing from the invention.

10b are the side members, which extend to 90 the feet 4b. The side members form part of the bracket 8b, which supports the air pump 6, while the bracket 11b supports the power reverse 7.

I claim:

1. The combination in the side frames of a locomotive, of a boiler mounted above the frames; a structure located between the boiler and the frames, but independent of the boiler and secured to the frames, the structure hav- 100

5 ing an overhanging bracket at one side, having pads to which an air pump is secured, and having a diagonal side member extending to a point above the frame at the opposite side of the locomotive from the air pump, said structure having a bracket on the opposite side from the air pump, and arranged to support a power reverse, one of the sides of the structure extending from one bracket to the other.

10 2. The combination of a main frame of a locomotive; a structure mounted on said frame and secured thereto and arranged to support an air pump at one side of the locomotive, and a power reverse on the opposite side thereof, said structure being independent of the boiler and the boiler supports.

3. An integral bracket for supporting an air pump and a power reverse, said support having feet which rest upon the main frame of the locomotive under the boiler and having vertically arranged pads, the pads on one side of the frame being arranged to support an air pump and the pads on the opposite side being arranged to support power reverse mechanism, said support being independent of the boiler and its supports.

4. The combination in a main frame of a locomotive, having two side members; a boiler mounted on supports above the main frame; and a support for the cylinder of an auxiliary apparatus, said support extending from one side member of the frame to the other side of said main frame and extending to one side thereof, said support being mounted on the two side members of the main frame and extending under the boiler but independent of the boiler and its support.

HARRY GLAENZER.
